UNITED STATES PATENT OFFICE.

EDWARD A. LANGENBACH, OF CANTON, OHIO, ASSIGNOR TO THE BERGER MANUFACTURING COMPANY, OF SAME PLACE.

DESIGN FOR A FINISHING-PLATE.

SPECIFICATION forming part of Design No. 23,513, dated July 24, 1894.

Application filed May 28, 1894. Serial No. 512,800. Term of patent 7 years.

To all whom it may concern:

Be it known that I, EDWARD A. LANGENBACH, a citizen of the United States, and a resident of Canton, county of Stark, State of Ohio, have invented and produced a new Design for Finishing-Plates, of which the following is a full, clear, and exact description reference being had to the accompanying drawings, making part of this specification.

- 10 The accompanying drawing represents my design which consists of a square or rectangular metallic finishing plate A, divided into sub-divisions by series of short broken or intercepted oval ribs or upwardly projected portions a and b, extending across the plate on lines at right angles to each other, and rosettes or circular projections c, situated at a point where the ribs a and b would cross if continued, and the open space between the
- 15 ends of the ribs and the rosettes. Central to the squares or subdivisions formed by the ribs a, b, is a palmated figure or rosette h.

The four angles of each sub-division are connected by arcs k, of equal radius, formed by series of graded projections resembling beads, ²⁵ the larger one at the apex of the arc and the smaller ones at the ends of the arc, approximating the circular projections c.

The essential feature of my design, is a metallic finishing plate divided into sub-divisions by series of sectional or intercepted ribs, ³⁰ at right angles, the circular projections c, the open space between the ends of the ribs, and the raised circular projection, the rosette h, and beaded arcs k.

35 What I claim is—

The design for metallic finishing plates herein shown and described.

In testimony whereof I have hereunto set my hand this 5th day of May, A. D. 1894.

EDWARD A. LANGENBACH.
